(57) **CLAIM**

The ornamental design for a building, as shown and described herein.

DESCRIPTION

FIG. 1 is a perspective view of a building embodying our new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The broken lines depict portions of the building that form no part of the claimed design.

1 Claim, 6 Drawing Sheets
